UNITED STATES PATENT OFFICE.

JAMES CLAYTON, OF SEBAKWE, BABBACOMBE, ENGLAND, ASSIGNOR TO THE VISCOS COMPANY, OF MARCUS HOOK, PENNSYLVANIA, A CORPORATION OF PENNSYLVANIA.

SKEINING MACHINE.

Application filed October 12, 1920. Serial No. 416,536.

To all whom it may concern:

Be it known that I, JAMES CLAYTON, a subject of the King of Great Britain and Ireland, and a resident of Sebakwe, Babba-
5 combe, England, have invented certain new and useful Inventions in Skeining Ma-
chines, of which the following is a specifi-
cation.

My invention relates to skeining ma-
10 chines, and particularly to a machine for skeining artificial silk; although it will be readily understood that the same machine may be used for skeining threads or yarn of any type. Among the objects of my invention, may be particularly mentioned an im-
15 proved general construction and arrangement of parts with reference especially, first, to facilitate discharge of the skein reels; second, to halt the latter automatically after 20 a predetermined length of thread has been wound thereon; third, to provide an im-
proved traversing device for distributing the threads on the reels; and fourth, generally to improve the structure and arrangement 25 of parts as will be hereinafter described, or as shown in the accompanying drawings, in which—

Fig. 1 is a plan view of portion of a skeining machine in which my invention is 30 embodied in one form;

Fig. 2 is a section on the line 2—2, Fig. 1;

Fig. 3 is a side elevation of the roving arm and connections;

Fig. 4 is a plan of the latter showing its 35 drive connection to the reel spindle;

Fig. 5 is a longitudinal section through the end portion of the casing showing the reel drive spindle;

Fig. 6 is an enlarged section through the 40 reel drive casing showing the clutch opening gear;

Fig. 7 is an enlarged section showing the skein reel in collapsed position;

Fig. 8 is a similar view showing the skein 45 reel in operative position; and

Fig. 9 is a partial side elevation of a reel of modified construction.

Inasmuch as the present invention is concerned particularly with elements of a 50 skeining machine which have to do with the skeining reel, its support, collapse and drive, the illustration of a complete machine is deemed unnecessary. I have therefore shown only the longitudinal rail 15 of the 55 frame and the driving shaft 16 arranged

above and extending parallel therewith the length of the machine. Upon the rail 15 are mounted at suitable intervals, inclined reel posts 17, preferably in balanced pairs forming V or Y units secured to the rail 15 by 60 bolts 18 passing through the base flanges 19. The posts form housings for the reel driving spindles 20 which approach each other at their lower ends and are supported in step bearings 21 carried by the posts. 65

The drive of each of the spindles 20 is taken from the main shaft 16, through a clutch comprising a sleeve 22 free on the

spindle 20 and provided at one end with a worm wheel 23 meshing with a worm on the 70

driving shaft 16, and at the other end with a friction disc 24. A cooperating clutch disc 25 is carried by the sleeve 26 keyed to the spindles 20 and normally pressed

against the disc 24 by spring 27. The sleeve 75

26 is engaged by a clutch releasing fork 28 pivoted at 29 to the post 17 and connected at its opposite end by a rod 30 to lever 31.

The latter is pivoted to the post 17 at 32 (Fig. 6) and has a handle end 33 project- 80

ing through the post for manual operation when desired. The lever 31 also carries on the stud 34 a gear wheel 35 meshing with a 85

cooperating gear 36 driven by a worm 37 on the reel drive spindle 20. The teeth on 90

the gears 35 and 36 are of unequal number, the gear wheel 35, for instance, having 28 teeth, and the gear wheel 36 having, for in- 95

stance, 27 teeth. Upon the gear 35 is se- 100

cured a hunting tooth 37 adapted to cooper- 105

ate with a similar hunting tooth 38 carried by the gear wheel 36. By reason of the unequal number of teeth in the periphery of the gears 35 and 36, it is obvious that 110

the hunting teeth 37 and 38 will not be brought into engagement until the spindle

30 has rotated a predetermined number of times, dependent upon the number of rev- 115

olutions which is desired for the reel in order to form a skein of desired length. When the hunting teeth 37 and 38 engage, how- 120

ever, the gear wheel 35 is lifted, since the

stud 39, on which the gear 36 is journaled, 125

is rigid with the post 17, while the stud

34 is mounted on the lever arm 31. The 130

lifting of the gear 35 obviously carries up 135

with it the end of the lever 31, to which

the connecting rod 30 is attached, and the 140

clutch lever 28 is shifted in a direction to 145

open the clutch and halt the drive of the 150

spindle 20. This automatically halts the rotation of the reel, and the attendant is thereby notified that the skein is full and should be removed.

5 It will be noted that the hunting tooth 38 is formed at the end of a rod 40 sliding in guides 41 and 42 against the action of a spring 43, and is provided with a stop pin 44 working in a slot 45 in the guide 41. In 10 order to maintain the clutch open during the removal of the skein from the reel, a catch 46 is mounted on the lever 31, and, in the open clutch position, engages beneath the plate 47 on the post 17. After the skein 15 has been removed and it is desired to start the reel in operation again, the operative has but to depress the free end of the catch 46. If the gears have not passed the point at which the hunting teeth 37 and 38 are in 20 displacing engagement, so that the gear wheel 35 is automatically drawn down into mesh with the gear wheel 36 by the pressure of the clutch spring 27, it is merely necessary for the operative to lift the hand lever 25 31, thus forcing the gear 35 down into mesh with the gear 36, against the action of the spring 43, and permitting the clutch 24—25 to close under the operation of spring 27. During this movement the stop pin 44 passes 30 downward in its guide slot 45. The drive of the reel is thus resumed.

At its upper end the reel drive spindle 20 is journaled in a bushing 48 (Fig. 5) adjacent the head of the post 17, and is provided beyond the journal with a bevel gear 49 meshing with a bevel gear 50 on the reel axis 51. The latter is journaled in a sleeve 52 (Figs. 7-8) having a ring head 53 surrounding the neck of the plug 54, which 35 closes the upper end of the post 17 to which it is pinned at 55 and 56. A cap 57 houses in the bevel gears 49 and 50 located in the end recess 58 in the plug. Fast with the reel axis 51, which is hollow, is the hub 59 40 of the reel, so that the latter is rotated by the drive of the axis 51. On the hub 59 are fixed spider arms 60, to which are pivoted at 61 the brackets 62 carrying, or formed in one with, the reel bars 63. The several 45 brackets of the reel bars are provided with slotted webs 64, in the slots 65 of which work pins 66 carried at the outer ends of a longitudinally movable spider 67, the hub of which is secured by a set screw 68 to a collar 55 69 free on the rod 70, which passes through the reel axis 51 and the reel hub 59, the latter being slotted at 71 to accommodate the set screw 68. A retaining ring 72 is pinned to the reduced end of the rod 70 to 60 hold the collar 69 in position thereon, and to insure its longitudinal movement with the rod. The rod 70 is jointed at its inner end to a lever 73 pivoted at 74 on the plug 54, and connected at its opposite end to an out- 65 wardly extending lug 75 on the ring head

53 of the reel arm 52. This connection is effected by a stud pin 76 passing through a slot 77 in the lever arm to permit play between these parts.

Upon the completion of a skein the operative grasps the cap 78 at the outer end of the reel arm sleeve 52 and pulls the latter downward and outward to the position shown in dotted lines in Fig. 1. This motion not only 70 swings the reel from its normal horizontal position to a downwardly inclined position 75 for the convenient removal of the skein, but also collapses the reel so that the skein is loose thereon. The collapsing motion is caused by the swinging of the ring head 80 53 around the plug 54, inasmuch as the lever 73 is shifted from its normal position shown in Fig. 8 to the discharge position shown in Fig. 7, with the result that the rod 70 is drawn inward and the movable hub 67 85 shifted toward the fixed hub 60. This motion forces the pins 66 through the inclined guide slots 65 in the bracket web 64, thus drawing together the free ends of the reel bars 63. After the skeins have been re- 90 moved, the return movement of the reel arms 52 by the operative displaces the movable hub 67 outward under the action of the lever 73 and rod 70, so that the reel is again expanded to its normal position shown in 95 Fig. 8.

A modified construction is indicated in Fig. 9, in which the reel bars 79 are more completely collapsed than in the construction first shown. As here indicated the 100 spider 80, which corresponds to the spider 60 of Figs. 7 and 8, supports the reel bars 79 through links 81 and 82, the latter slotted at 83 and extending downward into pivoted connection with the movable spider hub 84. 105 Obviously, upon the longitudinal displacement of the latter, the reel bars are collapsed with a parallel ruler motion, accentuated at the movable hub end by reason of the slotted connection 83, so that the skeins are readily 110 removed from the down end of the collapsed reel.

In its normal skeining position, the reel arm, whether of the construction shown in Figs. 7 and 8, or that shown in Fig. 115 9, is restrained, during the winding of the skein, by a spring-pressed pin 85, mounted in a bracket 86 at the head of the post 17, and having a beveled end which takes into a similarly shaped recess 87 in the outer 120 end of the lug 75 on the ring head 53. The downward pull exerted by the operative, when swinging the reel arm to discharge position, suffices to force the pin 85 downward out of the detaining engagement 125 which is automatically restored when the reel is swung again into operative position.

The traversing mechanism is illustrated on an enlarged scale in Figs. 3 and 4. As here shown the traverse arm 88 has a 130

forked end with guide eyes 89 for the thread leading to the reel, so that two skeins are simultaneously formed thereon side by side.

The traverse arm 88 is supported at one end on a post 90, free to rock in a standard or bracket 91 mounted on the rail 15 intermediate the reel posts. Connected to the arm 88 by a universal joint 92 is a connecting rod 93 having at one end a ring 94 (Fig. 6) surrounding the eccentric 95 on the reel drive shaft 20. Obviously, during the drive of the reel the eccentric 95 rotates and imparts a back and forth roving motion of the arm 88 to distribute the thread on the reels.

While the construction shown is well adapted for the purposes set forth, modifications and variations of structure will readily occur to those dealing with the problem, without departing from what I claim as my invention.

I claim—

1. In a skeining machine, a frame, an inclined post mounted thereon, a reel arm pivoted on the post, and means for swinging the said arm from skeining to discharge position.

2. In a skeining machine, a frame, an inclined post mounted thereon, a reel arm pivoted on the post, and means for swinging the said arm from skeining to discharge position, together with means for collapsing the reel to facilitate the discharge.

3. In a skeining machine, a frame, an inclined post mounted thereon, a reel arm pivoted on the post, and means for swinging the said arm from skeining to discharge position, together with means automatically operated by the swinging of said arm to collapse the reel and thus facilitate its discharge.

4. In a skeining machine, a reel supporting arm normally maintaining the reel in horizontal position during the skeining operation, and means for shifting said arm to downwardly inclined position to facilitate the discharge of the reel skein therefrom.

5. In a skeining machine, a reel supporting arm normally maintaining the reel in horizontal position during the skeining operation, and means for shifting said arm to downwardly inclined position to facilitate the discharge of the reel skein therefrom, together with means for collapsing the reel.

6. In a skeining machine, a reel support-

ing arm normally maintaining the reel in horizontal position during the skeining operation, and means for shifting said arm to downwardly inclined position to facilitate the discharge of the reel skein therefrom, together with means for automatically collapsing the reel toward the free end of the arm on its movement to downwardly inclined position.

7. In a skeining machine, a frame, an inclined post thereon, a reel drive shaft passing through said post, a reel arm extending from said post in horizontal position during the skeining operation, and means for swinging said reel arm on said post to downwardly inclined position to facilitate the discharge of the wound skein.

8. In a skeining machine, an inclined post, a reel supporting arm pivoted thereon, catch means for maintaining said arm in horizontal position for the skeining operation, said arm being rotatable, on release of the catch, to downwardly inclined position to discharge the skein.

9. In a skeining machine, a branched post having oppositely inclined pillars, a reel supporting arm pivoted on each pillar, means for maintaining said reel arms normally in horizontal position for the reeling operation, said arms being rotatable to downwardly inclined position for the discharge of the skeins reeled thereon.

10. In a skeining machine, a branched post having oppositely inclined pillars meeting at an angle at their lower ends, a drive shaft passing through said post at the juncture of said pillars, reeling mechanisms carried by said pillars, and a driving element on said shaft common to said mechanisms, and to which the latter are operatively connected.

11. In a skeining machine, an inclined post, a reel supported thereon in normally horizontal position, a reel-drive shaft within the post, an eccentric on said shaft, in combination with a vertical standard spaced from the post, a traversing arm pivoted on said standard, and an operative connection from said traversing arm to the eccentric on the reel drive shaft, for the purpose described.

In testimony whereof I have signed my name to this specification.

JAMES CLAYTON.
